Specification for Design.

Patented Apr. 12, 1921.

Application filed August 9, 1920. Serial No. 402,444. Term of patent 7 years.

To all whom it may concern:

Be it known that I, HERMAN T. MENDELSOHN, a citizen of the United States, and a resident of the city of New York, borough of Manhattan, in the county and State of New York, United States of America, have invented a new, original, and ornamental Design for a Netted Fabric, of which the following is a specification, reference being had to the accompanying drawing, forming

part thereof, which shows my design as embodied in a netted fabric.

The figure represents a plan view of one repeat of my design as embodied in a netted fabric.

What I claim and desire to secure by Letters Patent is:

The ornamental design for a netted fabric, as shown.

HERMAN T. MENDELSOHN.
